UNITED STATES PATENT OFFICE.

GEORGE G. FLOYD, OF CHICAGO, ILLINOIS, ASSIGNOR TO AMERICAN STEEL FOUNDRIES, OF NEW YORK, N. Y., A CORPORATION OF NEW JERSEY.

CAR-TRUCK.

1,116,050.

Specification of Letters Patent.

Patented Nov. 3, 1914.

Application filed June 8, 1914. Serial No. 843,600.

To all whom it may concern:

Be it known that I, GEORGE G. FLOYD, a citizen of the United States, and resident of Chicago, in the county of Cook and State of Illinois, have invented certain new and useful Improvements in Car-Trucks, of which the following is a specification.

My invention relates to car trucks and has particular reference to a novel connection 10 between a side frame and journal box of a car truck.

In order to maintain the standard coupler high above the rails as required by the Master Car Builders' Association, it is desirable 15 that the car body and the trucks should be likewise maintained at the proper height. However, in the use of car wheels which are turned down after a certain degree of wear has occurred, the mass of metal worn off 20 the wheel reduces the height of the structure superposed thereon. In order to obviate this difficulty I have conceived the idea of maintaining the side frames of the truck at the proper vertical height by inserting one 25 or more shims underneath the side frame at the point of engagement with the journal box providing a bolt and slot connection between the side frame and journal box which will permit of the insertion or removal of 30 the shim without interfering with the emergency connection between the box and the frame. In order to carry this into effect I provide a slotted lug on the side frame and a pair of ears on the journal box, the ears 35 having registering apertures in line with the slot through the lug. By passing a bolt through the apertures thus formed, the side frame may be raised or lowered as required by the condition of wear of the wheels.

40 The invention will be more readily understood by reference to the accompanying drawings, wherein,

Figure 1, is a front elevation of a portion of a side frame carrying a journal box, 45 the parts being constructed in accordance with my invention; Fig. 2 is a transverse section through the side frame showing the journal box in elevation, the parts being in the position of original assembling; that is, 50 when the wheels are of the full diameter; Fig. 3 is a view similar to Fig. 2, but showing the condition of the parts after wear has taken place on the wheels, the same having been turned down, a shim being inserted 55 between the frame and the box in order to compensate for the loss in diameter of

the wheels, and, Fig. 4 is an enlarged section on the line 4—4 of Fig. 2.

Referring more particularly to the drawings it will be seen that I provide a side 60 frame 10, with jaws 11, between which a journal box 12, is held, the journal box having side flanges 13, coöperating with the jaws of the side frame. The flanges 13, are extended across the top of the box as at 14, 65 and are of increased height in order to accommodate one or more shims 15, which may be inserted between the box and the frame. Projecting outwardly from the web of the side frame 10, is a lug 16, having a slot 17, 70 therein, Projecting upwardly from the journal box 12, are ears 18, having registering apertures 19, these apertures when the parts are in position being in line with the slot 17. A bolt 20, is adapted to be passed 75 through the aligned openings and serves as a means for preventing separation of the parts in emergencies.

As indicated by the line 21, extending between Figs. 2 and 3, the side frame is maintained at a fixed height irrespective of the reduction in diameter of the wheels such as indicated by the line 22 in Fig. 3, this being accomplished by the insertion of the shim 15, between the frame and box. It will be 80 noted that the shim is securely held in place against any possibility of removal being restrained by the jaws 11, on the side frame 85 and the flanges 14 on the box.

It will be understood that flanges adapted 90 to provide a stop similar to that used on the sides and top of the journal box 12 are usually of a height corresponding to the width of their base. However, the flanges 14 are constructed of a greater height than the 95 width of their base, this to provide for the insertion of the shims 15 when required. In the claims I have used the language "said flanges being of a height greater than necessary in order to properly engage said frame 100 when said frame is in contact with the box," as referring to flanges of the size just described.

I claim:

1. In a car truck the combination of a side 105 frame and a journal box with which said frame coöperates said box having vertical flanges on its top wall, said flanges being constructed of a height sufficient to properly engage said frame when said frame is separated from the box by the insertion of a shim 110 therebetween, substantially as described.

2. In a car truck, the combination of a side frame having pedestal jaws, a journal box adapted to be held between said jaws, said box being provided with vertical flanges on its top wall, said flanges being constructed of a height sufficient to properly engage said frame when said frame is separated from the box by the insertion of a shim

therebetween, said shim being held against horizontal displacement by said jaws and the vertical flanges on the box, substantially as described.

GEORGE G. FLOYD.
